Primary Examiner — Cynthia R Underwood(74) *Attorney, Agent, or Firm* — Howard & Howard Attorneys PLLC(57) **CLAIM**

The ornamental design for an accessory for a tabletop, as shown and described.

DESCRIPTION

FIG. 1 is a perspective view of an accessory design, showing my new design within an environment of use;

FIG. 2 is another perspective view of an accessory of FIG. 1;

FIG. 3 is a top plan view of the accessory of FIG. 1;

FIG. 4 is a side elevation view of the accessory of FIG. 1, with all sides being identical thereto; and,

FIG. 5 is a bottom plan view of the accessory of FIG. 1. The broken lines in FIG. 1 illustrating a table including a tabletop represents an environment of the accessory for the tabletop, and forms no part of the claimed design.

1 Claim, 2 Drawing Sheets(56)
